UNITED STATES PATENT OFFICE.

MORRIS LEVINE, OF WEEHAWKEN, NEW JERSEY.

WOVEN WILLOW CHAIR.

Application filed September 3, 1921. Serial No. 498,925.

To all whom it may concern:

Be it known that I, MORRIS LEVINE, a citizen of the United States, residing at Weehawken, in the county of Hudson and State 5 of New Jersey, have invented new and useful Improvements in Woven Willow Chairs, of which the following is a specification.

My improvements relate particularly to the construction of chairs consisting mainly 10 of woven willow work combined with suitable supporting frame work in a manner well known in the art, and my object mainly is to reinforce the seat and transmit the train of use thereof directly to the legs and 15 frame work of the chair, in such manner as to prevent sagging of the seat, and incidentally to render the whole structure more rigid and durable, all as hereinafter more fully set forth.

20 In the accompanying drawings:

Fig. 1, is a top view of the seat and lower portion of a woven willow chair embodying the essential features of my invention, the back of the chair being omitted;

25 Fig. 2, is a central vertical section upon plane of line 2—2 Fig. 1;

Fig. 3, is a view of the under side of the parts shown in Fig. 1;

30 Fig. 4, is a perspective view of the skeleton seat bottom reinforcement frame;

Fig. 5, is a detail view, in elevation, illustrating the character of the leg and seat brace joints;

35 Fig. 6, is a sectional detail taken upon plane of line 6—6, Fig. 5;

Fig. 7, is a sectional detail taken upon plane of line 7—7, Fig. 3, illustrating the character of the joint between skeleton seat bottom reinforcement frame and the braces.

40 S represents the seat weave, and s, the skirt weave, which, with the U-shaped seat frame s', and the "dowel" legs d, d', are of usual construction, the willow weave for this reason being indicated only in part for 45 convenience and clearness of illustration of the novel features, which are the skeleton seat-bottom reinforcement frame B, and the braces b, b', used in conjunction therewith.

The skeleton seat bottom frame B, consists preferably (although not necessarily) 50 of the side members b', b', and parallel cross members b², b², b². It may be attached rigidly to the under side of the seat, although this is not absolutely essential, since 55 it is supported by the braces b, b', its main function being to reinforce and sustain the

seat weave, and not only distribute the strain of use, but also to transmit the strain to the legs d, d',—at the same time acting as a binder and reinforcement to the said legs 60 d, d', themselves by tying and coupling them together centrally.

The upper ends of the braces b, b', are countersunk in sockets formed for the purpose in the under side of the reinforcement 65 frame B, and are also rigidly secured to the latter by nails or equivalent means; these sockets extend in the direction of the length of the braces, as seen in Figure 7, so that the latter may be simply inserted endwise 70 therein and easily adjustable therein, as occasion may require, and said braces have their lower ends rigidly secured to the legs d, d', by nails or equivalent means, and the willow strands of the skirt weave are en- 75 twined around these lower joints, as indicated in the drawings, particularly in Figs. 5 and 6 thereof. Preferably two braces b, b', are provided for each leg of the chair, although I do not limit myself in this respect. 80 It is to be understood that my skeleton seat-bottom reinforcement frame is supplemental to and independent of the seat frame proper.

Thus reinforced and sustained, the seat cannot sag, nor deteriorate in appearance; 85 and the whole structure of the chair is rendered more substantial and durable. Furthermore, my method of reinforcement is simple and inexpensive, and does not interfere with or materially change, the structure 90 of this type of chair as heretofore known in the art.

What I claim as my invention and desire to secure by Letters Patent is,

A chair construction including a seat 95 weave and an apron weave, a seat frame about which said seat weave is woven, a supplemental seat frame independent of said woven seat and arranged beneath and supporting said woven seat, diagonal braces 100 rigidly connected to the chair legs near their lower ends and having their upper ends inserted in sockets in said supplemental frame and permanently held therein, the apron weave being extended down around 105 said legs and woven thereabout to embrace the lower ends of said braces, thereby firmly holding the same in position.

MORRIS LEVINE.
